UNITED STATES PATENT OFFICE.

WILLIAM H. EBELHARE AND CLARENCE G. ARVIDSON, OF INDIANAPOLIS, INDIANA,
ASSIGNORS TO THE STENOTYPE COMPANY, OF INDIANAPOLIS, INDIANA.

TYPE-WRITING MACHINE.

1,273,338.

Specification of Letters Patent. Patented July 23, 1918.

Application filed November 21, 1916. Serial No. 132,613.

To all whom it may concern:

Be it known that we, WILLIAM H. EBELHARE and CLARENCE G. ARVIDSON, citizens of the United States, and residents of Indianapolis, in the county of Marion and State of Indiana, have invented certain new and useful Improvements in Type-Writing Machines; and we do hereby declare the following to be a full, clear, and exact description of the invention, such as will enable others skilled in the art to which it appertains to make and use the same.

This invention relates to improvements in typewriting machines and more particularly to paper feeding and guiding means especially adaptable for use with stenographic typewriting machines,—one object of our present invention being to provide simple and efficient mechanism which will operate accurately to feed the paper a definite distance for line spacing upon the manipulation of a key or plurality of keys.

A further object is to provide ratchet feed operating means which shall be so constructed that the same shall be practically noiseless in operation.

With these, and other objects in view, the invention consists in certain novel features of construction and combinations of parts as hereinafter set forth and pointed out in the claims.

In the accompanying drawings; Figure 1 is a plan view of a stenographic typewriting machine embodying our improvements; Fig. 2 is a longitudinal sectional view; Fig. 3 is an enlarged transverse sectional view through the paper feeding and guiding mechanism; Fig. 4 is an enlarged side elevation of said mechanism; Fig. 5 is an enlarged detail view showing the ratchet devices, Fig. 6 is a detail view of nut, and Fig. 7 is a detail view of spring washer 35^a.

1 represents the outer frame or casing of the machine, and 2 an inner frame which carries the operating mechanism of the machine, said inner frame being removably secured in the outer frame or casing 1 by means of screws 3 passing through the top of the latter and entering the top of said inner frame 2. A tray 4 to receive the paper strip 5 is located under the frame 1 and is secured to the latter by means of screws 6 which enter lugs 7 on the frame 1, said screws also serving to secure rubber feet 8 to the machine. The tray 4 is made with a

telescopic section 4^a which, when the machine is in use will be moved rearwardly to receive the paper as it comes from the machine.

The frame 2 is provided at its rear end 60 with arms 9, to which the forwardly projecting arms 10 of a supplemental frame 11 are secured,—said supplemental frame constituting, in effect, a part of the inner frame 2 in which the operating mechanism is supported. The supplemental frame carries a platen 12 which also constitutes a part of paper feeding mechanism, as hereinafter specifically explained. The platen 12 may comprise a cylinder 13 provided with a suitable flexible covering and with heads 14—15, the latter being provided with hubs 16—17 mounted to rotate upon a shaft 18. This shaft passes through the sides of the frame 11 and through the cylinder 13 and its heads. One end of the shaft 18 may be threaded to enter a threaded hole in one side of the frame 11, and the other end of said shaft may be provided with a slot 19 to receive a screw driver, as clearly shown 80 in Fig. 3.

The key board 20 of the machine occupies the open front portion of the main frame 1 as indicated in Figs. 1 and 2 and the key levers 21 are pivotally mounted on a rod or 85 shaft 22 in the lower portion of the inner frame 2,—adjustable springs 23 being provided to maintain the key bars in and return the same to normal position. The key levers 21 project upwardly and rearwardly from 90 their pivotal mountings and are operatively connected with bell cranks 24,—the latter being connected with type bars 25 for operating the latter,—all as specifically described in our application for patent, Serial No. 95 125,225 filed October 12, 1916. The keyboard is provided with a spacing key 26 and the lever of this key may be provided with a lug 27 (Fig. 2) with which one end of a spring 28 is attached and the other end of 100 this spring may be adjustably connected with the top of the frame 2.

The roller 12, forming a part of the paper feed mechanism as well as the platen roller for the type, is driven step-by-step when 105 the keys are operated, by means of ratchet devices. These comprise a ratchet wheel 29 (preferably having fine teeth) which may be secured to one end of the roller by means of a collar or nut 30 screwed on the hub 110

17 of the head 15 at one end of the core 13 of the roller and serving to clamp the ratchet wheel to said head. A pawl carrier 31 is mounted loosely on the collar or nut 30 5 and the latter is provided with an annular flange 32 which lies against one face of said pawl carrier. A pawl 33 is pivotally attached to the carrier 31 and pressed into engagement with the ratchet wheel by means 10 of a spring 34. A disk or ring 35 is mounted on the roller head 15 so as to be movable independently of both the roller and the ratchet wheel and between said disk and ratchet wheel, a spring washer 35^a may be 15 located. This disk or ring is provided with an annular flange 36 which encircles the ratchet wheel 29, and the flange 36 is provided with a notch 37 through which the pawl 33 projects to engage the ratchet 20 wheel. One wall of the notch 37 is beveled as shown at 38, so that when the pawl begins its retrograde movement it will ride on said beveled surface 38 and thus be disengaged from the ratchet wheel, thus preventing 25 noise which would otherwise occur should the pawl be permitted to drag backwardly of the teeth of the ratchet wheel. The flange 36 of the disk or ring 35 is provided also with a slot 39, and a pin 40 on carrier 31 30 is adapted to move from one end to the other of said slot 39. During such initial return movement of the carrier, the pawl will ride upon the beveled surface 38 and thus be moved out of engagement with the ratchet wheel. During the remainder of the 35 return movement of the carrier and its pawl, the pin 40 engaging one end of the slot 39, will cause the flanged disk or ring to move with said pawl and its carrier and thus the 40 pawl will be held out of engagement with the ratchet wheel during the complete retrograde throw of the same.

The ratchet mechanism is controlled by the operation of the key levers through the 45 medium of a universal bar 41 and connections between the same and the pawl carrier. The universal bar 41 is disposed transversely in the lower portion of the framework somewhat in advance of the pivotal mountings of the key levers so as to be actuated by the latter. The bar 41 is provided at its ends with arms which are pivotally connected with the frame 2 in line with the pivotal mountings of the key levers and said bar is spring sustained, all as fully shown and described in our application Serial No. 125,224, filed October 12, 1916.

The arm 42 at one end of the universal bar (the pivotal mounting of said arm being indicated at 43, Fig. 4) engages the bifurcated arm of a bell-crank lever 44, pivotally mounted on the frame at 45. The upwardly projecting arm 46 of the bell-crank is connected by means of an L-shaped link 47, with the pawl carrier 31. A spring 48 is con-

nected with the arm 46 of the bell-crank to insure the proper return of the parts.

From the construction and arrangement of parts above described, it is apparent that when a key lever (or any number of them) 70 is depressed, motion will be imparted through the medium of the universal bar, bell crank 44 and link 47 to the pawl carrier, thus causing the operation of the ratchet devices to turn the roller 12 for feeding the paper and that when the key lever is released, the parts will be returned to their normal positions. 75

To insure the proper and positive feeding of the paper when the roller 12 is operated as above described, auxiliary feed rollers 49 are provided and pressed toward said roller 12 so that the paper will be grasped by the coöperating rollers and moved the proper distance without danger 80 of slipping.

The rollers 49 are mounted on a shaft 50 and the latter is mounted at its respective ends in slightly elongated holes 51 near the forward ends of links 52. These links are 90 provided at their rear ends with collars or hubs 53 secured to a shaft 54 mounted at its ends in the sides of the supplemental frame 11. A bar 55 is hung from the shaft 50 and may be conveniently made of sheet 95 metal with stiffening flanges 56 at its edges and perforated lugs 57 at its ends loosely mounted on the shaft 50. Pins 58 secured to the bar 55, depend therefrom and pass loosely through holes in the bottom member 100 of the frame 11. Springs 59 encircle these pins and bear at their respective ends against the bottom of frame 11 and the bar 55, so as to force the latter upwardly pressing the auxiliary feed rollers toward the 105 roller 12.

The rear ends of the links 52 are provided with inwardly projecting lugs 60 which serve as guides for the edges of the paper strip. 110

A paper guide apron 61 is disposed under the roller 12 and is provided with ears 62 mounted loosely on the shaft 50. The forward portion of the apron is curved upwardly approximately concentric to the roller 12 and its rear portion is bent to form a curved lip 63 which guides the paper over the shaft 54. The apron 61 is provided with slots 64 for the accommodation of the feed rollers 49 and said apron is maintained yieldingly in position by means of a spring 65. This spring loosely encircles the shaft 50 and its respective ends engage said apron and the bar 55.

An upper paper guide 66 is pivotally 125 mounted in the frame 11 somewhat in rear of the roller 12 and made with a depending flange 67 having a toothed paper severing edge 68. The guide 66 is provided with lugs or ears 69 projecting over the roller 12 and 130

serve as mountings for small feed and guide rollers 70 which bear upon the paper passing over said roller. These rollers are normally pressed downwardly on the roller 12 by the action of a spring 71 and the guide member 66 is provided with an arm 72 whereby the same may be manually operated to raise the roller 70 when the paper strip is first threaded through the feeding mechanism.

10 The paper strip is placed in the tray 4 in folded condition and when the tray is in use with the telescopic section 4^a extended, the paper strip, after passing the paper feeding mechanism, will become deposited in a 15 folded pile within the extended section 4^a of the tray.

As clearly shown in Fig. 2, the paper strip 5 passes over the guide apron 61 and between the roller 12 and the rollers 49; then approximately half way around the roller 12 and past the printing position; then under the rollers 70; then under the guide 66, and finally to the extended section 4^a of the tray.

Various changes might be made in the details of construction of our invention without departing from the spirit thereof or limiting its scope and hence we do not wish to restrict ourselves to the precise details herein set forth.

30 Having fully described our invention what we claim as new and desire to secure by Letters-Patent, is:—

1. In a typewriting machine, the combination with feeding means, of a ratchet wheel connected therewith, an oscillatory pawl carrier, a spring-actuated pawl mounted on said carrier, a disk mounted to move independently of said ratchet wheel, said disk having a flange provided with a slot for the 35 passage of the pawl, and one end of said slot being beveled, and means for causing said disk to move with the pawl carrier during a portion of the movement of the latter.

2. In a typewriting machine, the combination with feeding means, of a ratchet wheel connected therewith, an oscillatory pawl carrier, a spring-actuated pawl mounted on said carrier, a disk movable independ-

ently of said ratchet wheel and having a flange projecting over the periphery of the 50 ratchet wheel, said flange provided with a slot for the passage of the pawl and one wall of said slot being beveled, and a pin-and-slot connection between the pawl carrier and said flanged disk.

3. In a typewriting machine, the combination with feeding means, a ratchet wheel connected therewith, key lever mechanism and a universal bar having a rearwardly projecting arm at one end, of an oscillatory 60 pawl carrier, a pawl mounted thereon to engage the ratchet wheel, a bell-crank having one of its arms loosely connected with the arm of the universal bar, and a link pivotally connected with an arm of said bell-crank and with said pawl carrier.

4. In a typewriting machine, the combination with a platen roller and key-operated means for turning the same step-by-step, of a shaft disposed under said roller, means for 70 supporting said shaft and permitting vertical movement of the same, rollers mounted on said shaft and coöperable with the platen roller, a bar hung on said shaft, guide pins for said bar, and springs on said pins tending to press the bar upwardly.

5. In a typewriting machine, the combination with a frame, a platen roller mounted in said frame, and means for operating said platen roller to feed a paper strip, of 80 links connected with said frame and provided with guide lugs, a shaft mounted in said links, feed rollers on said shaft and co-operative with the platen roller, and spring-operated means tending to press said shaft 85 and rollers upwardly toward the platen roller.

In testimony whereof, we have signed this specification in the presence of two subscribing witnesses.

WILLIAM H. EBELHARE.
CLARENCE G. ARVIDSON.
